UNITED STATES PATENT OFFICE.

ELNATHAN COLE, OF LOS ANGELES, CALIFORNIA, ASSIGNOR TO COLE MANUFACTURING COMPANY, A CORPORATION OF CALIFORNIA.

GAS-RADIATOR.

1,269,907.

Specification of Letters Patent. Patented June 18, 1918.

Application filed October 13, 1917. Serial No. 196,521.

To all whom it may concern:

Be it known that I, ELNATHAN COLE, a citizen of the United States, residing at Los Angeles, in the county of Los Angeles and 5 State of California, have invented a new and useful Gas-Radiator, of which the following is a specification.

My invention relates to the art of heating and ventilation.

10 The principal object of the invention is to provide a gas radiator of simple form and construction having certain new and useful features hereinafter pointed out.

In the art of heating, it is common practice 15 to provide gas radiators which are placed in the room to be heated and which are supplied with a gas burner which is utilized to heat the air in the radiator. Such radiators are in general open to certain objections, 20 among which may be mentioned the smothering of the fire when the radiator is first started, or, if the radiator is so arranged that it readily starts, the inefficiency of the radiator after it is in operation, and the 25 cooling and condensation of the water vapors in the radiator in such a manner as to interfere with the draft.

My invention is designed to overcome all 30 of these difficulties, and in addition to have certain advantages which will be set forth hereinafter, or will be evident to one skilled in the heating art after an examination of the drawings and the following description.

In these drawings:

35 Figure 1 is a perspective view of a radiator embodying my invention, the walls thereof being partly broken away to better illustrate the internal construction.

40 Fig. 2 is a section through the radiator, showing its internal construction.

In the form of the invention illustrated in these drawings, an outer shell 11 is provided, this shell being mounted on suitable legs 14 and having a suitable top 15 terminating in 45 a screened opening 16. Located inside the shell 11, and equally spaced therefrom all around, is a heating box 21 in the bottom of which a gas burner 22 is placed. The burner 22 is supplied with a combustible mixture 50 from a mixer 23, the supply of gas to which is controlled by a key 24. A pilot burner 25 controlled by a valve 26 may be supplied if desired. Extending longitudinally through the heating box 21 is a primary par-

titon 31, this partition going to the extreme 55 bottom of the heating box 21 and extending from end to end, being tightly secured to the bottom and ends. An opening 32 is left between the top of the primary partition 31 and the top of the heating box 21. The partition 31 consists of three main portions, a lower portion 33 which is substantially vertical, an inclined portion 34 which extends over and above the burner 22, and a vertical portion 35.

Secured to the side of the heating box 21, slightly above the center thereof, is a second or deflecting partition 41. This partition is secured to the side of the box and to either end, and covers a flue 42 which may 70 be connected to a suitable chimney. A small opening 43 is left between the lower end of the deflecting partition 41 and the inclined portion 34 of the partition 31. A series of holes 44 admit air to the bottom of the fire 75 box 21 around the burner 22. Small openings 45 admit auxiliary air to the space directly below the deflector 41.

The method of operation of the invention is as follows:

The burner 22 being lighted, hot gases ascend through the space between the primary partition 31 at the side of the box, passing through the opening 32 and downwardly through the opening 43 into the 85 space under the deflector 41 and outwardly through the flue 42. The inclined portion 34 of the partition 31 is considerably heated by the burner 22, and this heating sets up a secondary circulation through the holes 45 and 90 through the flue 42, so that a slight vacuum is created through the opening 43, this vacuum tending to draw the products of combustion downwardly through the deflector 41 into the flue 42. The hot gases are, however, 95 pocketed temporarily in the top of the heating box 21, and during the time that they are in this box they are constantly in contact with the walls thereof which are considerably heated and which give up their 100 heat to the air inside the shell 11 surrounding the box 21. This air in the shell 11 is constantly drawn in from the bottom, passing upwardly through the shell 11 and outwardly through the screened opening 16. 105 The cooling of the gases in the heating box 21 tends to partially condense the water vapor, which is, however, reheated and re-

vaporized in passing through the opening 43 along the inclined portion 34 of the partition 31. By supplying the auxiliary circulation through the openings 45, an immediate draft is created through the flue 42 as soon as the burner 22 is lighted. This draft is sufficient to start the main circulation through the openings 32 and 43, so that this main circulation can be relatively stagnant. 10 By making the circulation stagnant the products of combustion may be greatly lowered in temperature before being passed outwardly through the flue 42, and a very high efficiency can be secured.

15 I claim as my invention:—

1. A gas radiator comprising an outer shell open at the bottom and having an outlet opening at the top, a heating box within said outer shell spaced apart therefrom at 20 the sides and top, a vertically disposed partition in said heating box extending from the bottom to a point near the top of said heating box, a burner on one side of said partition, a flue outlet in the wall of said 25 heating box on the other side of said partition and extending through the outer shell, said heating box having openings in the bottom thereof on each side of the partition, and a deflector plate secured to the inner 30 wall of said heating box above said flue out-

let and extending downwardly and inwardly beyond the flue outlet.

2. A gas radiator comprising an outer shell open at the bottom and having an outlet at the top, a heating box within said outer shell spaced apart therefrom, a flue outlet in the rear wall of said heating box extending through the rear wall of the outer shell, a deflector plate secured to the rear wall of the heating box and extending inwardly and downwardly beyond the flue outlet, a partition in said heating box extending from the bottom of the box to a point near the top of the same and forming a passage between the upper end of the partition and the top of the heating box, said partition having a vertical portion below the flue outlet, an inclined portion below and adjacent to the lower edge of said deflector plate and a vertical portion above the inclined portion, and a burner in said heating box under the inclined portion of the partition, said heating box having openings in the bottom thereof on each side of the partition. 50

In testimony whereof, I have hereunto set my hand at Los Angeles, California, this 29th day of September, 1917.

ELNATHAN COLE.
